UNITED STATES PATENT OFFICE.

MORRIS C. STURMAN, OF CHICAGO, ILLINOIS, ASSIGNOR TO SANDEL MANUFACTURING COMPANY, OF CHICAGO, ILLINOIS, A CORPORATION OF ILLINOIS.

DESIGN FOR A SMOKING STAND.

Application filed September 15, 1927. Serial No. 23,411. Term of patent 3½ years.

To all whom it may concern:

Be it known that I, MORRIS C. STURMAN, a citizen of the United States, and residing at 3842 Congress Street, Chicago, Illinois, have invented a new, original, and ornamental Design for a Smoking Stand, of which the following is a specification, reference being had to the accompanying drawing, forming a part thereof.

The figure is a perspective view of a smoking stand showing my new design.

I claim:

The ornamental design for a smoking stand as shown.

MORRIS C. STURMAN.
